United States Patent Office

Des. 176,542
Patented Jan. 3, 1956

176,542

JAR

Arnold I. Lorenzen, Toledo, Ohio, assignor to Owens-Illinois Glass Company, Toledo, Ohio, a corporation of Ohio

Application November 19, 1953, Serial No. 27,672

Term of patent 14 years

(Cl. D58—25)

Fig. 1 is a front elevational view of a jar showing my new design; and

Fig. 2 is a bottom plan view.

I claim:

The ornamental design for a jar, substantially as shown.
